Primary Examiner — Jonathan J Han*(74) Attorney, Agent, or Firm* — Sterne, Kessler, Goldstein & Fox, P.L.L.C.(57) **CLAIM**

The ornamental design for a sole, as shown and described.

DESCRIPTION

FIG. 1 is a right side view of a sole showing the claimed design; and,

FIG. 2 is a bottom view thereof.

The dashed broken lines in the figures show portions of the sole and environment that form no part of the claimed design.

The dot-dash broken lines in the figures show boundaries that form no part of the claimed design.
